CLAIM

The ornamental design for a litter scoop, as shown and described.

DESCRIPTION

FIG. 1 is a top perspective view of a litter scoop in accordance with our new design;

FIG. 2 is a bottom perspective view thereof;

FIG. 3 is a top view thereof;

FIG. 4 is a bottom view thereof;

FIG. 5 is a side view thereof;

FIG. 6 is a back view thereof; and,

FIG. 7 is a front view thereof.

The broken lines shown represent unclaimed features of the litter scoop and form no part of the claimed design.
